FEED-WATER APPARATUS FOR BOILERS

Leuell W. Jeffords, Chicago, Ill., assignor to
Roma Jeffords, Chicago, Ill.

Application November 6, 1944, Serial No. 562,211

6 Claims. (Cl. 122—456)

1

This invention relates to feed water apparatus for boilers and is more particularly concerned with an apparatus which does not require the use of a feed pump or injector for supplying feed water to a boiler.

Another object of this invention is to provide a feed water apparatus of this type which may be employed to supply feed water from either a supply of water under pressure, such as the city water main, or from a water storage supply tank of the type employed to receive condensate returning through the steam lines.

It is a further object of this invention to provide a feed water apparatus which conserves steam in operation by utilizing same to preheat the feed water before it enters the boiler.

Another object of this invention is to provide a feed water apparatus of a vacuum-gravity type embodying automatic control means for supplying feed water to a boiler as required to maintain the water level in the boiler between predetermined levels.

Another object of this invention is to provide an automatic control system in which means are provided for discontinuing the flow of fuel to a boiler in the event the water therein drops below a predetermined level.

Another object of this invention is to provide either a continuous or intermittent flow of feed water to a boiler for maintaining the water within the boiler between predetermined levels.

A further object of this invention is to provide a feed water apparatus which is relatively inexpensive in construction, reliable in operation, and embodying a minimum number of moving parts to insure that the apparatus will not readily get out of order.

This invention embodies other novel features, details of construction, and arrangement of parts which are hereinafter set forth in the specification and claims, and illustrated in the accompanying drawings wherein:

Fig. 1 is a side elevational view showing an improved feed water apparatus arranged for use in supplying feed water from a water supply line to a steam boiler.

Fig. 2 is a wiring diagram illustrating the means employed for automatically controlling the flow of water through the feed water apparatus to a boiler.

Fig. 3 is a side elevational view illustrating a modified form of this invention in which feed water is drawn from a condensate tank upwardly through the feed water apparatus for delivery into the boiler by gravity.

2

Referring now to the drawings for a better understanding of this invention and more particularly to Figs. 1 and 2 therein, the feed water apparatus is shown as comprising a tank 11 having a partition 12 provided therein to define a primary chamber 13 and a transfer chamber 14. The partition 12 is formed with a centrally disposed port opening 16, of relatively smaller area than the conduit employed to supply water to the primary chamber 13, to permit feed water to flow from the primary chamber to the transfer chamber under control of a valve 17 actuated by a solenoid 18. Water is drawn into the primary chamber 13 through a supply pipe 19 and past a check valve 21.

A pipe 22 leads from the bottom of the transfer chamber to a steam boiler 23. A check valve 24 is interposed in the pipe 22 to prevent a reverse flow of water from the boiler to the transfer chamber. A steam line 26 is connected between the boiler and the upper end of the transfer chamber, and the flow of steam therethrough is controlled by a valve 27 which is opened and closed by means of a solenoid 28. A by-pass steam line 29 leads from the pipe 26, between the valve 27 and transfer chamber, to the upper end of the primary chamber 13. A check valve 31 is interposed in the by-pass steam line 29 to prevent a reverse flow of fluid from the primary chamber 13 to the transfer chamber 14 when the valve 27 is closed.

In the operation of the apparatus thus described water is drawn from the supply line 19 into the primary chamber 13 by a vacuum produced within the transfer chamber 14 while the valve 17 is in open position, after which the valve 17 closes the port 16. In the event the water level in the boiler 23 is below a predetermined level as illustrated in Fig. 2, the solenoid 18 is energized to open the valve 17 to permit the water within the primary chamber 13 to pass through the port 16 into the transfer chamber 14. When the water level within the transfer chamber rises to a predetermined level, the solenoid 18 is de-energized to permit movement of the valve 17 to its closed position against the port 16. The valve 27 in the steam line 26 is then opened by means of the solenoid 28 to permit steam to flow from the boiler 23 into the primary chamber 13 and the transfer chamber 14. When the pressure within the transfer chamber 14 is equal to the pressure within the boiler 23, the feed water will pass by gravity from the transfer chamber 14 through the pipe 22 to the boiler. The by-pass pipe 29 is provided to equalize the pressures on

opposite sides of the valve 17 in order to maintain same against the port opening 16 when steam is introduced into the transfer chamber.

After the water leaves the transfer chamber 14, the steam supply valve 27 is automatically closed and the valve 17 is opened to permit water to flow from the primary chamber 13 through the port opening 16 into the transfer chamber. This new supply of water acts to condense the steam and thereby create a vacuum within the transfer chamber to draw feed water through the pipe 19 into the primary chamber 13.

The solenoids 18 and 28 are energized by means of an electrical circuit including suitable relays and electrodes of the type now commonly employed for automatically controlling the water level within boilers. The present circuit contemplates the use of three electrodes 36, 37 and 38 mounted within a suitable housing 39 disposed adjacent the normal water line of a boiler and having inlet pipes 41 and 42 leading from the interior of the boiler to the interior of the housing 39. A pair of electrodes 43 and 44 are provided within the transfer chamber 14, the electrode 43 being disposed adjacent the bottom thereof and the electrode 44 being disposed approximately $\frac{1}{3}$ of the distance between the bottom and the top of the transfer chamber.

One circuit is completed from the upper electrode 44 through a lead 46 to a switch terminal 47 and thence through a relay 48 and a secondary transformer winding 49 to the ground. A holding circuit is provided for the relay 48 by a lead 51 which extends from the lower electrode 43 to a switch 52 thence through the relay 48 and transformer winding 49 to the ground.

Another circuit is completed from the electrode 38 through a lead 53 to a switch terminal 54 and thence through a relay 56 and secondary transformer winding 57 to the ground. A holding circuit is provided for the relay 56 by means of a lead 58 extending from the electrode 37 to a switch 59 and thence through the relay 56 and secondary transformer winding 57 to the ground.

A third circuit is completed by means of a lead 61 which extends from the electrode 36 to a relay 62 and thence through a secondary transformer winding 63 to the ground.

The windings 49, 57 and 63 form secondary windings for transformers 64, 66, and 67, respectively. The transformers 64, 66 and 67 are provided with primary windings 68, 69 and 71, respectively, which are connected to a source of current by means of leads 72 and 73 having a suitable operable switch 74 interposed therein. The transformers are carefully matched and secondarily connected to their respective relays in a manner well known in this art, and the electrodes 36, 37 and 38 are suitably positioned so that a predetermined rise and fall of the water level acts to make or break the electrical circuits controlling the relays.

The electrode 36 is employed to control the supply of fuel oil or gas delivered through conduit 16 to the boiler. When the electrode 36 is in contact with the water within the boiler the relay 62 is energized to close a switch 77 in a circuit 75 leading from a source of current to a solenoid 78. When the solenoid 78 is thus energized, it acts to open a valve 79 to permit the fuel to flow through the conduit 16 to the boiler. In the event the water level within the boiler falls below the lower end of the electrode 36, the circuit to the relay 62 is broken and permits the switch 77 to open

and break the circuit to the solenoid 78 which, in turn, acts to close the valve 79.

The water control solenoid 18 is connected to a source of current through leads 81 and 82. A pair of switches 83 and 84 are interposed in the circuit and are adapted to be opened and closed responsive to energization and de-energization of their respective relays 56 and 48. A manually operable switch 86 may be provided in the circuit 82 if desired.

The solenoid 28 is connected to a suitable source of current through leads 87 and 88 having a switch 89 interposed therein for opening and closing the circuit responsive to de-energization and energization of the relay 48.

The apparatus thus described functions automatically to supply feed water to a boiler when the water level within the boiler falls below the lower end of the electrode 37 and thus breaks the holding circuit 58 through the relay 56. When the relay 56 is thus de-energized, the switch 83 closes the circuit 82 to the solenoid 18 which acts to raise the valve 17 away from the port 16. Water contained within the primary chamber 13 passes through the port opening 16 into the transfer chamber 14 until the water level therein rises to complete a circuit through the upper electrode 44, lead 46, relay 48, and secondary winding 49. The relay 48 is thus energized and acts to close the switches 52 and 89 and to open the switch 84. The opening of the switch 84 breaks the circuit to the solenoid 18 and causes the valve 17 to move to its closed position in seated engagement against the port opening 16. The closing of the switch 52 completes a holding circuit to the relay 48 which will be energized until the water level within the transfer chamber falls below the lower electrode 43. The closing of the switch 89 acts to complete the circuit 88 to the solenoid 28 to energize same and thereby open the valve 27 in the steam line 26 which leads from the boiler to the transfer chamber and also to the primary chamber through the by-pass 29. When the pressure within the transfer chamber 14 is equal to the pressure within the boiler, the water within the transfer chamber will flow by gravity through the pipe 22 and past the check valve 24 into the boiler. When the holding circuit 51 between the electrode 43 and relay 48 is broken by movement of the water level below the electrode 43, the relay 48 is deenergized and permits opening of the switches 52 and 89 and closing of the switch 84. The de-energization of the relay 48 thus completes the cycle of operation. The apparatus continues to operate automatically in the manner thus described until the water within the boiler rises into contact with the upper electrode 38.

When the water level within the boiler is in contact with the upper electrode 38 a circuit is completed through the lead 53, relay 56 and secondary winding 47 to energize the relay 56 which then acts to open the switch 83 and close the switch 59. Opening of the switch 83 breaks the circuit to the solenoid 18 to render same inoperative until the water level in the boiler falls below the electrode 37 which forms part of the holding circuit 58 for the relay 56.

It will thus be seen that the water level within a boiler may be maintained between two predetermined levels as determined by the position of the electrodes 37 and 38. If for any reason the water level within the boiler falls below the lower end of the electrode 36, the supply of fuel to the boiler will be cut off.

Fig. 3 illustrates a modified form of this invention in which the feed water for the boiler is stored within a condensate tank 101. Feed water is supplied to the condensate tank through a condensate return line 102 and a feed water line 103. The water level within the condensate tank is regulated by means of a pair of electrodes 104 and 106, the electrode 104 being connected in a circuit 107 leading to a switch terminal 108, thence through a relay 109 and secondary winding 111 of a transformer 112 to the ground. The electrode 106 is connected in a holding circuit 113 leading through a switch 114, relay 109 and secondary winding 111 to the ground. The primary winding 116 of the transformer is connected to a suitable source of current.

The supply of feed water through the pipe 103 is controlled by a valve 117 which is operated by means of a solenoid 118 connected to a suitable source of current through a circuit 119. A switch 121 is interposed in the circuit 119 to make or break the circuit leading to the solenoid 118 when actuated by the relay 109.

In the operation of this electric control means for regulating the water level within the condensate tank, a surface contact between the water and the electrode 104 acts to energize the relay 109 to complete the holding circuit through the switch 114 and to open the switch 121 in the circuit leading to the solenoid 118. De-energization of the solenoid 118 acts to close the valve 117 and to stop the flow of make-up water leading through the pipe 103 to the condensate tank.

When the water level within the condensate tank falls below the end of the electrode 106, the holding circuit 113 to the relay 109 is broken, thereby opening the switch 114 and closing the switch 121. The closing of the switch 121 causes the solenoid 118 to open the valve 117 to permit the make-up water to flow through the pipe 103 into the condensate tank.

In the operation of this modified form of the invention, it has been found that the vacuum created within the transfer chamber 14 by condensing of the steam therein serves to draw water upwardly through the pipe 19 and into the primary chamber 13. The distance the feed water may be drawn upwardly through the pipe 19 depends upon the tightness of the system, as any leakage of air thereinto will serve to offset the vacuum created within the transfer chamber 14. The apparatus disclosed in Fig. 3 is otherwise similar in operation and construction to the form of the invention illustrated in Figs. 1 and 2.

While the two forms of apparatus shown and described are designed to provide an intermittent flow of feed water to a boiler, it is obvious to those skilled in this art that a pair of tanks 11 could readily be connected and controlled for alternate operation to provide a continuous flow of feed water through a common supply pipe 22 to the boiler 23.

As is also well known in this art, it is desirable to provide relatively small quantities of make-up water to a boiler either in the form of a continuous flow or an intermittent flow in order to prevent deterioration of parts of a boiler due to chilling and consequent alternate contraction and expansion.

It will be noted in the operation of this apparatus that the steam employed for transferring feed water to a boiler is not wasted as it serves to preheat the feed water prior to its transfer into the boiler.

It will further be noted that the only heat loss

in the operation of this apparatus would be due to the radiation of heat from the tank 11 and the pipes 22, 26 and 29 and that this heat loss could be reduced to a negligible proportion by properly covering these parts with insulating material.

While this invention has been shown in but two forms, it is obvious to those skilled in the art that it is not so limited but is susceptible of various changes and modifications without departing from the spirit and scope of the claimed invention.

I claim as my invention:

1. In a liquid transfer device for a boiler, a transfer chamber having an outlet leading to the boiler, a primary chamber having a liquid inlet and disposed to supply liquid to said transfer chamber, a power actuated normally closed valve for controlling the passage of liquid from the primary chamber to the transfer chamber, electrical means having a connection to the boiler and responsive to the water level within the boiler for automatically opening said power actuated normally closed valve when the water within the boiler falls below a predetermined level, valve means operable for supplying steam to the transfer chamber to preheat the liquid therein and to force same therefrom, and electrical means for automatically controlling the alternate operation of said valves, said means including a pair of electrodes disposed within the transfer chamber and electrically connected for alternately operating said valves.

2. In a boiler apparatus of the character described, a primary chamber having a liquid inlet, a transfer chamber having a liquid outlet leading to the boiler, said primary chamber having a passage leading therefrom to the transfer chamber, a power actuated normally closed valve provided in said passage, electrical means having a connection to the boiler and responsive to the water level within the boiler for automatically opening said power actuated normally closed valve when the water within the boiler falls below a predetermined level, valve means operable for supplying steam to the transfer chamber, and electrical means for automatically controlling the alternate operation of said valves responsive to variations of the liquid level within said transfer chamber.

3. In a feed water apparatus for a boiler, a transfer chamber having a steam inlet and a water outlet leading to the boiler, power actuated valve means for controlling the flow of steam to said transfer chamber, power actuated normally closed valve means for controlling the flow of water to said transfer chamber, electrical means having a connection to the boiler and responsive to the water level within the boiler for automatically opening said power actuated normally closed valve when the water within the boiler falls below a predetermined level, and electrical means for controlling the alternate opening and closing of said valve means, said electrical means including circuits having electrodes disposed in spaced relation within said transfer chamber for controlling the operation of said valve means responsive to predetermined variations of the water level within the transfer chamber.

4. In a feed water apparatus for a boiler, a transfer chamber having a steam inlet and a water outlet leading to the boiler, power actuated valve means for controlling the flow of steam to said transfer chamber, power actuated normally closed valve means for controlling the flow of water to said transfer chamber, electrical means

having a connection to the boiler and responsive to the water level within the boiler for automatically opening said power actuated normally closed valve when the water within the boiler falls below a predetermined level, electrical means for controlling the alternate opening and closing of said valve means, said electrical means including circuits having electrodes disposed in spaced relation within said transfer chamber for controlling the operation of said valve means responsive to predetermined variations of the water level within the transfer chamber, and electrical means associated with the boiler and acting responsive to predetermined variations of the water level therein for controlling the operation of said other electrical means.

5. In a liquid feed device for a boiler, a primary chamber having a liquid inlet, a transfer chamber having a liquid outlet and a steam inlet leading to the boiler, said primary chamber having a passage leading to the transfer chamber, a power actuated normally closed liquid control valve interposed in said passage, electrical means having a connection to the boiler and responsive to the water level within the boiler for automatically opening said power actuated normally closed valve when the water within the boiler falls below a predetermined level, a steam control valve interposed in said steam inlet, an upper electrode disposed within said transfer chamber, a lower electrode disposed within said transfer chamber, electrical means associated with said upper electrode for closing said liquid control valve and opening said steam control valve when

the liquid within the transfer chamber rises into contact with the upper electrode, and means associated with said lower electrode for closing said steam control valve and opening said liquid control valve when the liquid level within the transfer chamber falls below said lower electrode.

6. In a liquid feed device for a boiler, a primary chamber having a liquid inlet, a transfer chamber having a liquid outlet and a steam inlet leading to the boiler, said primary chamber having a passage leading to the transfer chamber, a power actuated normally closed liquid control valve interposed in said passage, electrical means having a connection to the boiler and responsive to the water level within the boiler for automatically opening said power actuated normally closed valve when the water within the boiler falls below a predetermined level, a steam control valve interposed in said steam inlet, an upper electrode disposed within said transfer chamber, electrical means associated with said upper electrode for closing said liquid control valve and opening said steam control valve when the liquid within the transfer chamber rises into contact with the upper electrode, means associated with said lower electrode for closing said steam control valve and opening said liquid control valve when the liquid level within the transfer chamber falls below said lower electrode, said electrical means associated with said upper and lower electrodes within the transfer chamber being controlled by said first mentioned electrical means.

LEUELL W. JEFFORDS.
